US00D602485S

(12) **United States Design Patent**
Ting et al.

(10) **Patent No.:** **US D602,485 S**
(45) **Date of Patent:** **** Oct. 20, 2009**

(54) **NOTEBOOK COMPUTER**

(75) Inventors: **Chih-Kang Ting**, Yonghe (TW);
Chang-Ta Miao, Taipei (TW);
Gwo-Chyuan Chen, Taipei (TW)

(73) Assignee: **Quanta Computer Inc.**, Tao Yuan Shien (TW)

(**) Term: **14 Years**

(21) Appl. No.: **29/330,199**

(22) Filed: **Dec. 30, 2008**

(30) **Foreign Application Priority Data**

Nov. 12, 2008 (TW) 97306477

(51) **LOC (9) Cl.** **14-02**

(52) **U.S. Cl.** **D14/318**

(58) **Field of Classification Search** ..... D14/315-328, D14/455; D18/1, 2, 7, 11; 235/145 A, 145 R; 341/22, 23; 345/104, 156, 168, 169, 173, 345/87, 901-905; 361/680-686, 679.09, 361/679.27; 400/486, 489; 710/14

See application file for complete search history.
